KITE

Hing F. Chu and Helga M. Chu, Larchmont, N. Y.

Application June 27, 1944, Serial No. 542,384

9 Claims. (Cl. 244—153)

The present invention relates to kites and more particularly to kites which may be made in various ornamental forms and designs.

One object of the present invention is a kite construction that will fly more steadily and rise faster than known kite constructions.

Another object is to provide a kite construction having loose wings and loose wing tips to enable the wings to flap when in flight.

A further object of the present invention is to provide a kite of this character which may be easily assembled from a knock-down condition.

A still further object of the invention is to provide a kite construction utilizing a single bridle and without the conventional tail.

A still further object of the invention is to provide a kite construction which may be easily converted to a fixed wing kite in order to enhance the vacuum within the surface of the wings to increase its climbing speed and to give greater pull or power.

A still further object is to provide a kite having sound means which are actuated when the kite is in flight.

With the foregoing and other objects in view, the invention will now be more fully described, reference being had to the accompanying drawings in which:

Figure 1 is a rear elevational view of the kite.

Figure 2 is a front elevational view of the same kite and

Figure 3 is a front elevational view of a modified construction.

Referring more particularly to the drawing, the kite frame is comprised of a center vertical stick 10, body or wing sticks 11, head bracer stick 12 and tail construction stick 13. The various sticks are preferably of flexible material such as bamboo wood although such sticks could be made of rigid or preformed material. In the construction thus far defined, the wing sticks 11 and tail stick 13 are secured to the center stick 10 by means of string or equivalent material 14. The forward outermost portions of wing sticks 11 are suitably bowed by attaching string or wire 15 thereto and drawing same until the proper bow is secured and then fastening the ends to center stick 10.

The head bracer stick 12 suitably secured to center stick 10 and to the bowed portions of wing sticks 11 by means of string 16. Frictionally secured to the center stick 10 and above the bracer stick 12 is a collar 17 which in turn is secured by means of string 18 to a bow member 19. Across the free ends of the bow 19 is stretched a ribbon 20 capable of producing sound when drawn through the air. The ends of ribbon 20 are secured to the bow ends by means of caps 21 which caps are suitably slotted or bored whereby they are frictionally retained over the ribbon and bow ends.

The area defined by the bracer sticks 11, bracer stick 12 and tail stick 13 are covered by paper or other material 21. It will be noted that such paper covering is loose or unattached at points 5 outside the wing sticks 11 so as to give a flapping effect to the kite when in motion. Such covering is secured at its fixed points such as sticks 11 by means of cement, paste or the like.

At a point 22, preferably about seven and one-quarter inches from the top of sticks 10, a bridle 23 is secured for guiding the kite and restraining same. The bridle 23 may be attached to any other point on stick 10 depending on the size of the kite.

Referring now to the modified construction disclosed in Figure 3, the same reference numerals are used to denote such parts as correspond to Figures 1 and 2. The essential difference between Figures 1 and 2 and that disclosed by Figure 3 is that the latter has its covering 21 fixed instead of loose. This is accomplished by use of an additional body stick 24 suitably spaced from the top portions of sticks 11. Such additional stick 24 is bowed at its ends and such ends and the ends 25 of sticks 11 are lapped or crossed as at 25 and a string 26 secured over one of the lapped ends and tied to the opposite lapped ends. The covering 21 is then cemented around the stick 24, the surplus material being cut away. This construction creates a fixed vacuum effect within the wings as distinguished from the loose wing effect.

In constructing the kite disclosed in Figures 1, 2 and 3, only string, thread, thin wire and covering material such as Cellophane, silk, cloth or the like is used. The various sticks are preferably made of bamboo or the like material such as wooden dowels. However, rigid material which is preformed to the shapes of the various sticks may be used.

What is claimed is:

1. In a kite, a frame comprising a longitudinally extending center stick, crossed sticks secured upon said center stick in spaced relation to the upper end thereof and disposed in crossed relation to the center stick and each other, a brace mounted across the lower end of said center stick and projecting laterally from opposite sides thereof with its ends secured to lower ends of the crossed sticks and together with lower portions of the crossed sticks and the center stick forming the frame with a tail portion extending longitudinally of the frame, said crossed sticks being curved longitudinally by strands attached to the center stick and having upper portions 50 extending laterally from opposite sides of said center stick, a brace extending between the upper portions of said crossed sticks and across the center stick, a collar carried by the last mentioned brace and engaged about the upper end 55 of the center stick, a bowed stick mounted across

the center stick above said collar with its end portions projecting upwardly, a strand extending between and carried by ends of the bowed stick and constituting a vibratable sound producing member, and a covering sheet adheringly secured against the center stick and said crossed sticks and having free end edges and lower edge portions to provide the covering sheet with free portions disposed outwardly of said strands and constituting flaps adapted to flutter while the kite is in flight.

2. In a kite, a frame comprising a longitudinally extending center stick, crossed sticks secured in crossed relation to the center stick and each other and having upper wing portions extending laterally from opposite sides of the center stick and lower portions extending diagonally from opposite sides of the center stick and co-operating with the center stick to form a tail, a brace across the lower end of the center stick and secured to lower ends of the crossed sticks, cords secured to the center stick and extending diagonally upwards therefrom and secured to upper ends of the crossed sticks and holding the crossed sticks bowed, a brace extending between and secured to the wing forming portions of the crossed sticks, and a covering sheet secured against the center stick and portions of the crossed sticks at opposite sides thereof and having free portions projecting outwardly from the cords and the crossed sticks and adapted to flutter when the kite is in flight.

3. In a kite, a frame comprising a longitudinally extending center stick, crossed sticks secured in crossed relation to the center stick and each other, said crossed sticks being bowed longitudinally and having lower tail forming portions at opposite sides of the center stick and upper wing forming portions projecting from opposite sides of the center stick, and a covering sheet adheringly secured to the center stick and portions of the crossed sticks at opposite sides thereof, said sheet being free along its ends and along its lower edge between the tail forming portions of the crossed strips and its ends, and providing free flaps adapted to flutter when the kite is in flight.

4. In a kite, a frame comprising a longitudinally extending center stick, crossed sticks secured in crossed relation to the center stick and each other, said crossed sticks being bowed longitudinally and having lower tail forming portions at opposite sides of the center stick and upper wing forming portions projecting from opposite sides of the center stick, a covering sheet extending transversely of the frame and secured to the center stick and the crossed sticks, said sheet being free along its lower edge and at its ends to provide flaps adapted to flutter when the kite is in flight, a yoke carried by said center stick above the wing forming portions of the crossed sticks, and a ribbon extending between and secured to ends of said yoke and constituting a vibrator for creating sound when the kite is in flight.

5. In a kite, a frame including crossed sticks bowed longitudinally and having tail forming portions extending longitudinally of the frame and wing forming portions extending transversely of the frame, a covering sheet extending transversely of the frame and adheringly secured to

the crossed sticks, said sheet projecting outwardly from ends of the wing forming portions and being free along its ends and lower edges to provide flaps adapted to flutter when the kite is in flight, and means for bracing the crossed sticks.

6. In a kite, a frame including crossed sticks bowed longitudinally and having tail forming portions extending longitudinally of the frame and wing forming portions extending transversely of the frame, a covering sheet extending transversely of the frame and adheringly secured to the crossed sticks, said sheet projecting outwardly from ends of the wing forming portions and being free along its ends and lower edges to provide flaps adapted to flutter when the kite is in flight, a yoke extending transversely of the frame above the wing forming portions of the crossed sticks, and a strand extending transversely of said frame and secured at its ends to said yoke and constituting a wind actuated vibrator creating sound when the kite is in flight.

7. In a kite, a frame including crossed sticks bowed longitudinally and having tail forming portions extending longitudinally of the frame and wing forming portions extending transversely of the frame, a covering sheet extending transversely of the sheet and adheringly secured to the crossed sticks, a yoke mounted across the frame above the crossed sticks and having arms at its ends, and a strand extending between and secured at its ends to the arms and constituting a vibrator creating sound when the kite is in flight.

8. In a kite, a frame including a longitudinally extending center stick, crossed sticks secured upon the center stick in crossed relation to each other, the crossed sticks being bowed longitudinally and having tail-forming rear portions extending longitudinally of the frame at opposite sides of the center stick and wing-forming forward portions extending from opposite sides of the center stick, a stick mounted across the center stick and the tail-forming portions of the crossed sticks and projecting from opposite sides thereof and having its ends secured to ends of the wing-forming portions of said crossed sticks, a covering sheet secured to said sticks, a yoke mounted across the front end of the center stick and having forwardly projecting arms, and a strand extending between and secured to said arms and constituting a vibrator for creating sound when the kite is in flight.

9. In a kite, a frame including a longitudinally extending center stick, crossed sticks secured upon the center stick in crossed relation to each other, said crossed sticks being bowed longitudinally and having tail-forming rear portions extending longitudinally of the frame at opposite sides of the center stick and wing-forming forward portions extending from opposite sides of the center stick, a covering sheet adheringly secured to said sticks, a yoke mounted across the frame and secured to the center stick and having forwardly extending arms at its ends, a strand extending between and secured to said arms, and a bridle consisting of a single strand secured to the center stick adjacent the crossed portions of said crossed sticks.
